Patented Oct. 19, 1915.

FIG. 1

FIG. 2

FIG. 3

WITNESSES:

Charlton J. Milam.

G. E. Ferwilliger

Peter E. Embser, INVENTOR.
BY Clifford E. Denner, ATTORNEY.

UNITED STATES PATENT OFFICE.

PETER EMBSER, OF NEW YORK, N. Y., ASSIGNOR OF ONE-HALF TO JOHN A. MANSELL,
OF NEW YORK, N. Y.

PRINTER'S MITER-GAGE.

1,157,372.

Specification of Letters Patent.

Patented Oct. 19, 1915.

Application filed April 17, 1915. Serial No. 21,991.

To all whom it may concern:

Be it known that I, PETER EMBSER, a citizen of the United States, residing in the borough of Manhattan, city, county, and State of New York, have invented certain new and useful Improvements in Printers' Miter-Gages, of which the following is a specification.

In the art of printing, as is well known, it is frequently necessary to cut rules or leads at an angle of 45° in order to form mitered corners when the rules are set in position in the form at an angle of 90° to each other.

My invention relates to simple but accurate means for aiding a person operating a miter machine to cut a rule or lead to the exact length desired with accuracy and speed.

My device comprises a unitary structure which may be readily attached to an existing cutting machine.

In the accompanying drawings which form a part of this specification, Figure 1 is a perspective view of a cutter to which is attached one embodiment of my invention. Fig. 2 is a perspective view on an enlarged scale of my improved device. Fig. 3 is an enlarged, fragmentary view showing details of construction and Fig. 4 is a transverse sectional view on line IV—IV of Fig. 2.

Referring to the drawings in detail, the numeral 1 designates a cutting machine of well known design, having a bed plate 2 and a cutting knife 3, adapted to be oscillated about the shaft 4 by means of a handle 5, and the connecting links 6 and 7. This machine forms no part of my present invention but is shown merely to illustrate the mode of attaching and using my invention in connection with any well known or existing machine. The bed plate of the cutter is provided with an adjustable clamp 8, which is adapted to be held in place by manipulation of the thumb screw 9.

My improved gage consists essentially of a substantially triangular frame having a base member 10, an upright 11 and an inclined guide element 12 which is preferably provided with an upstanding, vertical flange 13. This entire structure may preferably be formed from a single unitary piece of sheet metal by die-stamping and bending into the shape shown in the drawings. At the apex between the upright and the guide

member a pair of slots 14 and 15 are formed, one below the other, and into the slot 14 is introduced a slide 16 which is provided near its lower extremity with an upturned lug 17, and at its upper end with a thumb piece 18. The slide is urged against the inner side of the inclined guide member by means of a U-shaped spring 19, which encircles the upright and has its ends, 20 and 21, bent down an incline passing through the slot 15, and exerting pressure against the lower side of the slide, thereby holding it in place. The lug 17 is adapted to be forced into any one of a series of slots or holes 22 formed in the central portion of the guide member, thus definitely positioning the lug with respect to the guide, the spring, meanwhile, holding it in such adjusted position. A second lug, 23 may be formed near the upper end of the slide and adapted to enter an open slot 24 in the upper extremity of the guide member when the slide is at or near its lowest position.

When it is desired to miter a slug to any desired length the lug 17 is placed in the particular slot 22 which corresponds to the length of the slug which it is desired to cut, after the base 10 has been clamped in position in the machine shown in Fig. 1, with the forward edge 25 adjacent to the cutting edge of the miter. In order that this may be done with greater facility a scale of numbers, preferably on the em system, is provided in connection with the slots 22, indicating the length of a slug which will be cut by the miter when one end is held against the lug 17. The flange 13 forms a guide for the side of the slug so that the operator, having introduced the end of the slug to be cut through the aperture 26, and holding it in engagement with the lug 17 and flange 13 by means of the left-hand, may readily operate the machine with his right hand, thus cutting the slug with absolute precision.

It will be understood that for ordinary mitering the angle between the base 10 and the inclined guide member 12 will be 45° , although this angle may, of course, be altered to suit special conditions.

While I have illustrated and described one specific embodiment of my device, I appreciate that it is susceptible of wide application, and I do not desire to be limited to the precise structure shown and described.

Having thus described my invention what

I claim as new herein and desire to secure by Letters Patent is:

1. A miter gage having a base, an inclined guide mounted thereon and provided with a plurality of spaced slots therein, a stop adapted to coöperate with said guide and means for locking said stop in adjusted position in any one of said slots.
2. A miter gage having a base, an inclined guide mounted thereon and provided with a plurality of spaced slots therein, a slide adapted to move longitudinally with respect to said guide, a stop mounted on said slide and means for retaining said stop in adjusted position in any one of said slots.
3. A miter gage having a base, an inclined guide mounted thereon and provided with a plurality of spaced slots therein, a slide beneath said guide, a stop on said slide and a spring for urging said slide into contact with said guide.
4. A miter gage having a base, an inclined guide mounted thereon, a post for supporting the upper end of said guide, said guide being provided with a plurality of spaced slots therein, a member adapted to slide longitudinally with respect to said guide, a stop on said member adapted to project through any of said slots when in adjusted position and a U-spring surrounding said post and having a portion forcing said member into contact with said guide.
5. A miter gage having a base, an inclined guide mounted thereon, a post for supporting the upper end of said guide, said guide being provided with a plurality of spaced slots therein, a member adapted to slide longitudinally with respect to said guide, a stop on said member adapted to project through any of said slots when in adjusted position, a U-spring surrounding said post and having a portion forcing said member into contact with said guide, and a vertical lateral flange on said guide.
6. A miter gage having a frame composed of a single piece of sheet metal formed into a base, a guide inclined thereto, a flange on said guide and a post for supporting the upper end of said guide.
7. A miter gage having a frame composed of a single piece of sheet metal formed into a base, a guide inclined thereto, a flange on said guide and a post for supporting the upper end of said guide, said guide being provided with spaced slots therein, a spring, a member longitudinally movable of said guide and normally forced in contact therewith by said spring, and a stop on said member adapted to project through any of said slots when in adjusted position.

In testimony whereof I have hereunto set my hand this 15 day of April, 1915.

PETER EMBSER.
